J. ZRADA

JEWELRY BOX

Filed Oct. 5, 1922

FIG. 2.

FIG. 1.

John Zrada
Inventor
J. H. Bryant, Attorney

UNITED STATES PATENT OFFICE.

JOHN ZRADA, OF CHICAGO, ILLINOIS.

DESIGN FOR A JEWELRY BOX.

Application filed October 5, 1922. Serial No. 3,892. Term of patent 14 years.

To all whom it may concern:

Be it known that I, JOHN ZRADA, a citizen of Poland, residing at Chicago, in the county of Cook and State of Illinois, have invented a new, original, and ornamental Design for Jewelry Box, of which the following is a specification, reference being had to the accompanying drawing, forming part thereof.

I claim:

The ornamental design for a jewelry box, as shown.

JOHN ZRADA.

Witnesses:

STANLEY BONLY,
JOHN ZBONOWSKI.
